Primary Examiner—Robert M. Spear*Assistant Examiner*—Susan E Krakower(74) *Attorney, Agent, or Firm*—Cantor Colburn LLP(57) **CLAIM**

I claim, the ornamental design for a workstation luminaire with reflective surface feature, as shown and described.

DESCRIPTION

FIG. 1 is a bottom perspective view of a workstation luminaire with reflective surface feature, showing my new design; and,

FIG. 2 is a bottom plan view thereof.

The break lines shown in FIGS. 1 and 2 of the workstation luminaire with reflective surface indicate the article has no specific length.
